(57) **CLAIM**

I claim the ornamental design for an auxiliary nursing base member, as shown and described.

DESCRIPTION

FIG. 1 is a front perspective view of the auxiliary nursing base member showing my new design;

FIG. 2 is a rear perspective view thereof;

FIG. 3 is a front view thereof;

Fig. 4 is a right side view with the left side view being a mirror image thereof;

FIG. 5 is a rear view thereof;

FIG. 6 is a top view thereof; and,

FIG. 7 is a bottom view thereof.
